UNITED STATES PATENT OFFICE.

EDWARD F. BEHNING, OF DETROIT, MICHIGAN, ASSIGNOR TO DIAMOND STATE FIBRE COMPANY, OF BRIDGEPORT, PENNSYLVANIA, A CORPORATION OF DELAWARE.

DRIVE CHAIN.

Application filed January 10, 1927. Serial No. 160,263.

This invention relates to drive chains, and more particularly to that type of chain which comprises a plurality of flat toothed links assembled in a manner hereinafter clearly set forth.

One of the objects of the present invention is to provide a chain of this type which shall be light in weight, strong, durable and silent and capable of withstanding corrosion to a much greater extent than chains as ordinarily manufactured.

The invention resides further in certain novel details of construction as hereinafter clearly set forth and as illustrated in the attached drawings, in which:

Figure 1 is a plan view of a section of chain made in accordance with my invention;

Fig. 2 is a side elevation of the chain section shown in Fig. 1;

Fig. 3 is a view in perspective of one of the links, and

Fig. 4 is a section on the line 4—4, Fig. 2.

In forming my chain, I prefer to form the links, which may be shaped as shown in Fig. 3, of a non-metallic material which shall be unaffected in an adverse way by oil, water, acids and other elements that might come in contact with the chain under operating conditions. As a material that I have found particularly well adapted for the purpose, I prefer to employ one of the laminated synthetic resin-bonded bodies, such as that known in the trade as "Celoron", which bodies are commonly composed of a number of sheets

of paper or fabric bonded together into a substantially homogeneous laminated body by means of a synthetic resin, such as bakelite, in its hard infusible and insoluble state. These bodies are particularly valuable for the present purpose by reason of their imperviousness to water, oil, acids and alkalies, and by reason further of their strength and toughness and noise-eliminating characteristics. These materials lend themselves further to use in my chain by reason of the fact that they may be manufactured in sheet form of thickness corresponding to the desired thickness of the individual links, the latter being punched or otherwise formed from the sheets with a material saving in the manufac-

turing cost. A further consideration which makes the use of this material of value is its comparative lightness affording a material reduction in the weight of the links and link units which results in reducing the stretch and whip of the unmched portion of the chain to a minimum.

In assembling the chain, the links 1 are pivotally secured together, as clearly illustrated, by means of rivets 2, these rivets being surrounded in each instance by a sleeve 3 which preferably is of the same composition as the links 1. The rivets 2 after being inserted with the sleeve 3 through the apertures 4 in the links 1 are turned over at the ends, it being preferred to insert washers 5 between the heads of the rivets and the ends of the sleeve 3 which extend beyond the periphery of the sleeve and hold the links 1 in position. It will be noted that with this arrangement only the ends of the rivets 2 are exposed, the rest being closely surrounded and protected by the sleeves 3 which constitute the bearings or pivots 4 for the links. It may be preferred to provide means for preventing relative rotation between the metal pin 2 and the sleeve 3, and this may be done in any one of a number of obvious ways. In the present instance, I have shown at one end of the rivet 2 a small longitudinal ridge or feather which enters a corresponding groove in the inside of the sleeve 3 and holds the parts relatively immovable.

Under certain operating conditions, such for example as in the crank case of an automobile, there is apt to be present a certain percentage of sulfuric acid. This acid corrodes and adversely affects the pins and links of chains of this general type as previously manufactured entirely of metal. Practically all of this corrosive effect is eliminated in the present instance as previously set forth by reason of the protection of the major portion of the pin by the bushing 3. What slight corrosion may occur in the pin 2 cannot interfere materially with the normal operation of the chain by reason of the fact that there is no frictional movement directly around the rivet 2, the links turning as previously described upon the bushing 3.

There may, of course, be considered modification in the form of link herein described and illustrated without departure from the invention.

5 I claim:

A power chain comprising a plurality of links formed of a non-metallic material com-

prising a hardened synthetic resin, metallic pins for pivotally securing said links together, and sleeves interposed between the pins and the links and also composed of a non-metallic body comprising a hardened synthetic resin. ¹⁰

EDWARD F. BEHNING.
